UNITED STATES PATENT OFFICE.

EDWARD J. RUQUET, JR., OF NEW YORK, N. Y.

CLAMP-BOLT.

1,343,089.

Specification of Letters Patent.

Patented June 8, 1920.

Application filed April 18, 1919. Serial No. 290,944.

To all whom it may concern:

Be it known that I, EDWARD J. RUQUET, Jr., a citizen of the United States, and a resident of New York city, Rosebank, borough of Richmond, county of Richmond, and State of New York, have invented a new and Improved Clamp-Bolt, of which the following is a full, clear, and exact description.

10 This invention relates to a new form of bolt. More particularly it relates to a clamp bolt for temporary use in holding material together. In ship and bridge building and in other constructional enterprises it is often necessary to employ temporary means for holding plates and other materials together while the permanent rivets and bolts are being driven.

It is, therefore, a purpose of my invention to provide a temporary bolt clamp capable of joining together firmly two pieces of material. My invention comprises a bolt embodying clamping means which may be inserted in registering holes of the material 25 to be clamped together. This clamp bolt is convenient and simple in its application and use, and is very quick to apply and remove.

A broad purpose of the invention is to 30 provide a form of slotted pin fitted with clamp means, the whole of which may be inserted through the hole formed in the ship plates to be temporarily bolted together.

35 Finally, it is an object of my invention to provide a form of clamp bolt device embodying the above utility characteristics which will be comparatively inexpensive to manufacture and positive in its application and use.

With the above and other objects in view the invention has relation to a certain combination and arrangement of parts, an example of which is described in the following specification, pointed out in the appended claims and illustrated in the accompanying drawings, wherein:

Figure 1 illustrates the initial application of the clamp bolt to plates for securing same together, and shows partial assembly of the parts prior to the final clamping action. This view is made in section.

Fig. 2 illustrates a sectional view of the clamp bolt in its completed application to 55 the plates showing same in clamped and fixedly secured relation.

Fig. 3 shows a sectional view through plates to be secured together, the view being taken from the side of Fig. 1 and Fig. 2.

Fig. 4 illustrates a sectional view taken 60 upon the line 4-4 of Fig. 1.

Fig. 5 shows the application of the clamp bolt with a clamp bar applied thereto, the clamp bar placing the bolts and plate under compression for finally securing the 65 plates together.

Fig. 6 shows a perspective view of a clamp guide member adapted to guide the clamping parts into position and clamp plates together. 70

Fig. 7 shows a perspective view of a clamp strut used in maintaining certain parts in fixed relationship.

Fig. 8 shows a perspective view of a slotted pin used in this device. 75

Fig. 9 shows one of a pair of key clamps used in this clamp bolt.

Fig. 10 illustrates a spreader key employed for spreading the key clamps into service position. 80

Fig. 11 illustrates a modified design of the clamp bolt.

Fig. 12 shows a perspective view of a form of wedge member used in connection with the modified design of the invention. 85

Referring now more in particular to the drawings, wherein the same reference characters are used to designate the same parts throughout the several views, the numeral 1 points out a clamp guide provided with a 90 conical shaped bore 2. Grooves 3 are formed in the conical bore. The surface or walls 3 comprising the groove extend parallel one with the other. On the underside of the clamp guide is formed arcuate projections or shoulders 5, which, as later seen, will function as a cam. Set screw holes 6 are tapped into opposite faces of the clamp guide and communicate with the grooves formed in the bore. The upper and lower 100 surfaces of the clamp guide will be finished parallel one with the other adapting it to fit properly with the associate parts of this clamp bolt. 95

A clamp strut comprising a base 8 integrally formed with a vertical supporting strut or post 9 fitted with an integral head 10 is employed in this clamp bolt. The inner face 11 is formed perpendicular to the plane of the base 8, and the outer face is serrated or knurled as indicated by 12. This element just described is one of a pair 105 110

adapted to be disposed in the slots 3 of the clamp base such that the adjacent vertical faces 11 are directed one toward the other, thus placing the knurled faces 12 in engagement with set screws screw-threaded into the bores 6.

A slotted pin comprising parallel members 14 formed by cutting a slot 15 through the body of the pin is provided and adapted 10 to be inserted through the bore of the clamp guide and guided into position by the clamp struts. This slotted pin is provided with double cam faces 16 integrally formed with the members 14. Rectangular heads 17 are 15 integrally formed on the free ends of the pin members.

A spreader key comprising a bar 19 square in cross-section and integrally formed with a head 20, which head has secured thereto a 20 lifting handle 21, is provided for co-operating with the assembled device, the function of which is to force certain members into service position.

A pair of key clamps is employed in this 25 device. These keys comprise a bar of material 23 square in cross-section and integrally formed with down-turned ends 24 forming a head on one end of the bar. The other end of the bar is curved as indicated by the number 30 25. This provides a cam face 26 formed on the curved end of the bar.

Referring now more in particular to the assembly views of the drawing, I have heretofore described the relative position of the 35 parts in the several views. The reference characters A and B designate two plates of material to be fastened together. This material may comprise ship-plates, bridge materials and others common in structural undertaking. The two plates to be temporarily secured together are provided with registering holes.

The clamp struts are applied to the face of one plate adjacent the hole formed therein, and the clamp guide placed in position 45 upon the two struts. The struts will fit into the grooves 3 of the guide as heretofore described. Set screws 28 are screw-threaded into the bores of the guide and loosely set 50 against the knurled faces of the clamp struts. The slotted pin will next be inserted and passed through bolt holes formed in the two plates, thus disposing the spreader cam 16 on the opposite side of the material from 55 the operator. The head 17 of the slotted pin will rest in contact upon the upper face of the clamp guide. The two clamp keys will next be inserted by passing the curve or cam shaped ends through the open slot of the 60 pin 14. The operator assembling the device will hold the two clamp keys in one hand and next insert the spreader key 19 by passing said key into the device between the adjacent faces of the key clamps.

65 This relative position of parts is illus-

trated in Fig. 1. The co-acting key clamps and spreader key will then be pushed all the way through until the head of the key lies in contact with the heads of the key clamps. This will force the key clamps into 70 position and downwardly in contact with the spreader cam 16. During this operation the set screws, which are preferably knurled on the surface end thereof, will be loosely engaged with the clamp struts. 75

A tightening or clamping bar comprising a forked cam 30 provided with a handle 31 is placed in position as illustrated in Figs. 3 and 5. The upper working face of the cam 30 fits the curved cam face of the 80 clamp guide, while the lower arcuate face of the cam 30 is formed eccentric to the upper face and works in contact against the plate A. By bringing pressure to bear 85 downwardly upon the handle 31, and thus properly manipulating the cam 30, this member can be made to slide under pressure beneath the clamp guide and lift all the parts into a very tight clamping relation 90 against the plates A and B. This action 90 lifts the spreader cam 16 in forceful engagement with the key clamps thus spreading them outwardly against the hole walls of the plates. Continued pressure exerted through the cam and bar will securely 95 clamp the plates A and B between the base 8 and the curved ends of the key clamps. The set screws will next be tightened securely against the inclined and knurled 100 face of the clamp struts, and the cam bar 100 removed. The parts are now clamped in position as illustrated in Fig. 2. Any parting tendency of the plates A and B will exert a downward pull upon the set screws. The inclined face of the clamp struts will 105 prevent the clamp guide and associate set screws from moving downwardly, and if any movement does take place will further tighten and more securely clamp together 110 the parts.

This clamp bolt can be quickly and easily assembled in the hole, and removed therefrom by one workman or mechanic, and will find broad range of uses in erecting structures as heretofore described. 115

Fig. 8 shows in perspective view my particular form of slotted pin designed for use in connection with any form of lifting or clamping means to be used for carrying out the purposes of this invention. In particular I claim the use of this form of slotted pin provided with a double faced cam and integral lifting head. It will be understood that this pin can be inserted through the holes of material to be fastened or clamped 120 together and the key clamps placed in position so that any form of clamping means may be used. I have illustrated two forms of clamping means in the drawings, one form residing in the cam bar design and 125 130

the other form residing in the driving wedge design at Fig. 11. It is obvious that many different forms of clamping or pressure means may be used for exerting pressure against the plates to be clamped, and I desire to include the various clamping methods which may be found suitable for use in connection with my form of slotted pin.

Figs. 11 and 12 illustrate a modified form 10 of the clamp bolt showing a simplified application of the device to clamp members A and B together in a tight relation.

In this modified application of the invention, the slotted pin 14 will be inserted into 15 the hole formed in the plates A and B and the key clamps and spreader key inserted in the usual manner. A pair of bifurcated wedge-shaped members 40 will then be pushed into place between the plate A and 20 the head 23 as illustrated in Fig. 11. The wedge-shaped members will straddle the clamp bolt assembly and will be driven into place one against the other causing the wedge-shaped surfaces to draw the clamp 25 bolt upwardly through the hole thus tightly clamping the two plate members A and B together.

This last described modified design of my invention may be used to great effect where 30 there is no vibration evident in the structure to be erected. Where there is a considerable vibrational activity throughout the plates A and B or other structures it will be preferable to use the other form of clamp bolt 35 as above described.

Having thus described my invention, what I claim as new, and desire to secure by Letters Patent is:

1. A clamp bolt for temporary erection of 40 structures comprising in combination, a clamp guide, a slotted pin inserted therein, key clamps fitting into the slotted pin, a spreader key for spreading the key clamps, and means for exerting lifting force on the 45 key clamps.

2. A clamp bolt comprising in combination, a clamp guide, a slotted pin inserted therein, a cam integrally formed with the slotted pin, key clamps fitting into the 50 slotted pin, a spreader key for spreading the key clamps, and means for exerting lifting force on the key clamps.

3. A clamp bolt comprising in combination, a clamp guide, a slotted pin inserted 55 therein, a cam integrally formed with the slotted pin, key clamps fitting into the slotted pin, a spreader key for spreading the key clamps, means for exerting lifting force on the key clamps, and clamp screws provided to hold the parts in position after the 60 lifting force has been removed.

4. A clamp bolt comprising in combination, a pair of clamp struts, a clamp guide fitted upon the clamp struts, the said elements 65 adapted to be mounted over register-

ing holes of materials to be fastened together, a pin passed through the clamp guide and through the registering holes, key clamps coöperating with the pin, and a spreader key inserted between the key 70 clamps adapted to spread the key clamps apart.

5. A clamp bolt for temporary erection 75 of structures comprising in combination, a clamp guide provided with cam surfaces cut thereon and a bore with grooves, clamp struts inserted in the bore of the clamp guide and placed adjacent registering holes in the material to be secured together, a pin passed through the bore of clamp guide and 80 through the hole of the material, a cam formed on the pin, and means passed through the bore and the holes for clamping the materials to be secured together.

6. A clamp bolt for temporary erection 85 of structures comprising in combination, a clamp guide provided with cam surfaces cut thereon and a bore with grooves, clamp struts inserted in the bore of the clamp guide and placed adjacent registering holes 90 in the material to be secured together, a pin passed through the bore of the clamp guide and through the hole of the material, means passed through the bore and the holes 95 for clamping the materials to be secured together.

7. A clamp bolt for clamping material together comprising in combination, a clamp guide, cam faces formed on the clamp guide, a pin carried by the clamp guide, a head 100 formed on the pin and resting in contiguous relation upon the clamp guide, a cam formed on the pin, key clamps mounted in the clamp guide, and cam faces formed on one end of the key clamps and adapted to engage the 105 cam of the pin.

8. A clamp bolt for clamping material together comprising in combination, a slotted pin member, a pair of bars with curved ends inserted in the slot of the pin member 110 and adapted to engage material to be clamped together, and means for drawing the slotted pin member and the bars tightly against the material to be clamped.

9. A clamp bolt for clamping material 115 together where the material has a hole formed therein comprising in combination, a pin adapted to be passed through the hole formed in the material, a head formed on the pin, means to coöperate with the pin 120 and adapted to engage the material to be clamped, and a wedge capable of being inserted between the head and the material to be clamped for drawing the device into clamped engagement with the material to 125 be clamped.

10. A clamp bolt for holding material together comprising in combination, a slotted pin, a pair of key clamps, a spreader key, a head formed on the slotted pin, and a wedge 130

inserted between the head and material to be clamped for drawing the slotted pin with the key clamps into clamping engagement with the material to be secured together.

5 11. A device of the character described for insertion in a hole formed in a plate or other material, comprising in combination, a pin consisting of two parallel spaced bars,

a cam integrally formed at the end of the bars, and a pair of spreader keys, cams 10 formed on one end of the spreader keys adapted to coöperate with the aforesaid cam faces of the pin member and adapted to wedge against the plate or material through which the device is inserted.

EDWARD J. RUQUET, Jr.
